US0D1045121S

(12) **United States Design Patent** (10) Patent No.: **US D1,045,121 S**
(45) Date of Patent: ** Oct. 1, 2024

(54) **SAMPLE INCUBATION AND TESTING DEVICE**

(71) Applicant: **Vax-Immune, LLC**, Houston, TX (US)

(72) Inventors: **Leonard E. Weisman**, Houston, TX (US); **Philip Michael Weiner**, Pontefract (GB); **Mika Nenonen**, Helsinki (FI); **Adrienne McNees**, Pearland, TX (US)

(73) Assignee: **Vax-Immune, LLC**, Houston, TX (US)

(**) Term: **15 Years**

(21) Appl. No.: **29/844,373**

(22) Filed: **Jun. 28, 2022**

(51) LOC (14) Cl. **24-02**

(52) U.S. Cl.

USPC **D24/216**

(58) **Field of Classification Search**

USPC D24/107, 108, 130, 133, 186, 216, 224,

(57) **CLAIM**

The ornamental design for a sample incubation and testing device, as shown and described.

DESCRIPTION

FIG. 1 is a perspective view of a sample incubation and testing device, showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is an exploded view thereof.

The broken lines in the drawings depict portions of the sample incubation and testing device and form no part of the claimed design.

1 Claim, 8 Drawing Sheets
